TOOTHBRUSH RETAINER

Benjamin Oshman and Joseph Oshman,
New York, N. Y.

Application August 2, 1940, Serial No. 349,606

2 Claims. (Cl. 206—15.1)

This invention relates to a tooth brush retainer, and its objects are to retain the brush efficiently in convenient location, to maintain it clean, dust-proof, sanitary, and out of contact with other articles, and to provide improved means for its rapid, ready, and convenient withdrawal from the container and reinsertion therewith.

Other objects and advantages will hereinafter appear.

In the accompanying drawing,

Fig. 1 shows a plan view of the tooth brush and container therefor of this invention.

Fig. 2 is an elevation of the tooth brush container shown in Fig. 1.

Fig. 3 is a plan view of the tooth brush retainer shown in Fig. 1, as it appears during the insertion and withdrawal of the tooth brush.

Fig. 4 is an end elevation of the tooth brush retainer shown in Fig. 1.

Figs. 5 and 6 show respectively a longitudinal cross-sectional plan view and an elevation of a modification of the invention.

Figs. 7, 8, are respectively a plan view and an elevation of another modification of the invention.

The tooth brush retainer 1, Figs. 1-4, comprises an elongated receptacle 2 consisting of two tray-like half members 3, 4, held to each other by a hinge 5, whereby said members may be disposed to a closed state, as shown in Fig. 1, or they may be swung about said hinge to an open position, as illustrated in Fig. 3. A leaf spring 6 secured to the members 3, 4 at 7 and having a pair of wings 8 presses with said wings against the sides of said members to normally maintain them in the closed state shown in Fig. 1. Each of the members 3, 4 is provided at the end opposite to the hinge 5 with an opposed cam 9 having inclined surfaces 10, 11, and the tooth brush 12 to be used with this retainer is provided with a portion 13 at the junction of its handle 14 and brush head 15, the sides of which portion are configurated similarly to the cams 9.

When the tooth brush 12 is to be inserted into the receptacle 2 for retention, the leading end 16 of brush head 15 strikes the cam surfaces 10 and thereby actuates the members 3, 4 to swing open as illustrated in Fig. 3 and permits the brush to enter completely into the retainer, whereupon the springs 8 close the receptacle, with the cams 9 in registry with the brush portion 13. When the tooth brush 12 is to be removed from the retainer, the inclined sides 17 of portion 13 bear against the cam surfaces 11, and thereby similarly open the receptacle members 3, 4, as shown

in Fig. 3, to permit the ready and convenient withdrawal of the tooth brush.

According to the modifications shown in Figs. 5, 6, the receptacle 2a comprising the retainer is of one piece, having a closed end 18 and an open opposite end provided with flexible door shutters 19. The brush handle 14 has its portion 13 configurated similarly to that shown in Fig. 1, and to the side-walls 20 of receptacle 2a are secured

10 opposed leaf springs 21 that normally register with the sides of brush portion 13. When the tooth brush is inserted into the receptacle 2a for retention, its bristles 22 open the shutters 19 to permit ingress and its end 16 spreads apart the springs 21 until the brush enters completely into the retainer, whereupon the springs 21 realign themselves to their normal form in registry with the tooth brush portion 13 to lock it in retained place and the shutters 19 spring back to closed position, as shown. Upon removal of the tooth

15 brush, the opposite action occurs with respect to the springs 21 and shutters 19, to permit the ready and convenient withdrawal of the tooth brush.

20 25 In modifications shown in Figs. 7, 8, the receptacle 2b of the retainer is similar to that shown in Fig. 5, and to its open end 23 are hinged at 24 cooperating cams 25 that are similar to the cams 9, of Fig. 1, and have integral therewith floorings 26 meeting each other at 27. Leaf springs 28 secured at 29 to the receptacle walls normally bear against the cams 25 and press the floorings 26 against each other at 27 under tension. From the foregoing descriptions it will be evident that

30 35 inserting the tooth brush 12 into the receptacle 2b for retention will spread the cams 25 apart to permit its ingress, and the springs 28 will restore said cams to locked engagement with the brush portion 13, the shutters 19 closing up the receptacle 2b. Upon withdrawal of the tooth brush from the container, the opposite action occurs in the manner illustrated and described in connection with the retainers shown in Figs.

40 45 1, 5.

Having thus described our invention, we claim:

1. A tooth brush retainer having the combination of an elongated receptacle open at one end for entrance and adapted to receive a brush-head when it is moved therewith longitudinally through said open end, a pair of cam-shaped members for retaining said brush-head within the receptacle each being hinged to said open end of said

receptacle to swing toward and away from each other, spring means normally impelling said members toward each other, said brush-head having a terminal and narrowed base, said members adapted to be actuated away from each other by said terminal of the brush-head to permit insertion of the brush-head into said receptacle and to then return into said narrowed base, and said narrowed base spreading said members apart during removal of the brush-head from the receptacle.

2. A tooth brush and retainer therefor comprising a receptacle open at one end for entrance and adapted to receive the head of said brush when it is moved thereinto longitudinally through 15 said open end, a pair of cam-shaped members for

retaining said brush-head within the receptacle each being hinged to said open end of said receptacle to swing toward and away from each other, spring means normally impelling said members toward each other, said brush-head having a terminal, said members adapted to be actuated away from each other by said terminal to permit insertion of the brush head into said receptacle, and said brush-head being configured at its base to conform to said members when contained within the receptacle and to spread said members apart during removal from the receptacle.
